UNITED STATES PATENT OFFICE.

JAMES W. CHRYSTY, OF PATASKALA, OHIO.

TYPE-WRITING MACHINE.

SPECIFICATION forming part of Letters Patent No. 393,142, dated November 20, 1888.

Application filed July 17, 1886. Serial No. 208,300. (No model.)

To all whom it may concern:

Be it known that I, JAMES W. CHRYSTY, a citizen of the United States, residing at Pataskala, in the county of Licking and State of Ohio, have invented new and useful Improvements in Type-Writing Machines, of which the following is a specification.

My invention relates to improvements in type-writing machines; and it consists of the peculiar combination and novel construction and arrangement of the various parts for service, substantially as hereinafter fully set forth, and specifically pointed out in the claims.

The primary object of my invention is to provide an improved type-writer which shall possess superior advantages over all others that have preceded it in points of compactness in arrangement of parts, so that it can be carried or transported with great ease, and which shall furthermore be cheap and comparatively inexpensive of manufacture and very simple and durable in construction.

Among other things my invention has, further, for its object to provide a simple, light, and compact type-cylinder which carries all of the letters and characters, that are arranged thereon in series around its periphery, and the cylinder is capable of oblique movement and lateral rotation to adapt one letter or character at a time to deliver its impression upon the paper affixed in a paper-carriage; to provide a single key which controls and actuates the type-cylinder to deliver its impression simultaneously with the depression of the key; to

provide a swinging key-board containing all of the characters and letters on the type-cylinder, over which board the key is moved or adjusted in operating the machine, so as to guide the operator; to provide an improved carriage for the paper on which the impressions from the type-cylinder are to be delivered, which is fed with a step-by-step motion and controlled and actuated by the swinging key-board, the latter being returned to its upright or normal position and the carriage simultaneously fed one step forward immediately after the delivery of each impression by the type-cylinder, so as to be in position for instant operation; to provide means for properly aligning and spacing the words, and, finally, to provide a space-key for feeding the carriage with a step-by-step motion independently of the swinging

key-board to effect the proper spacing between the words, all as hereinafter fully set forth.

In the accompanying drawings, which illustrate a type-writing machine embodying my invention, Figure 1 is a top plan view thereof. Figs. 2 and 3 are elevations taken from opposite sides of the machine. Fig. 4 is a vertical central transverse sectional view on the line *x x* of Fig. 1. Fig. 5 is a detached perspective view of the swinging frame for the key, together with the type-cylinder. Fig. 6 is an enlarged detail view of the type-cylinder. Fig. 65 7 is a view of the paper-carriage detached from the base-piece of the machine. Fig. 8 is a view of the space-key. Fig. 9 is a detail view of the mechanism to be actuated by the swinging key-board to feed the paper-carriage with a 70 step-by-step motion. Fig. 10 is a detail sectional view on the line *y y* of Fig. 4.

Referring to the drawings, in which like letters of reference denote corresponding parts in all the figures, A designates the base piece 75 or plate of a type-writing machine embodying my invention, upon which is supported the swinging key-board B, with the single key C, that is to be moved by hand over the key-board to actuate or depress the latter; D, the type-cylinder, which is controlled and actuated by the key C; and E, the paper-carriage, which has the paper to receive the impressions from the type-cylinder, the peculiar construction and arrangement of the several parts of which I 85 will now proceed to describe in detail.

The key-board B is preferably made curved or segmental in form and arranged in an inclined position, so that a support is provided for the hand of the operator, and the lower 90 edge of the said board is pivotally supported on the base-piece, as at *b*. The upper outer face of the key-board has a series of indentations or recesses, *b'*, formed therein, which are arranged in series transversely and longitudinally of the board, and opposite or in close proximity to each one of these indentations is indelibly stamped or impressed a letter, figure, or character, as shown in Fig. 1, the said indentations being preferably conical in shape, 100 so that a conical or tapered point of the key C will easily and readily take or fit into the indentations, which is very important when the operator is writing very rapidly. I pref-

erably arrange the letters, ordinals, and characters on the key-board as follows, although I would have it understood that I do not intend to confine myself to the precise disposition of the said parts: The letters of the alphabet are first arranged in three rows or series at the upper end of the key-board, with nine (9) to a series, thus making twenty-seven (27) letters altogether. Then follow the numerals or ordinals, from one (1) to nine, (9,) and, finally, the punctuation marks or characters, the dollar-mark, (\$,) and the cipher, (0.)

The key C is made in the form of a rod or pin, with a conical or tapered end that is adapted to readily and freely enter the conical indentations or recesses of the swinging key-board, and one end of this key carries a finger or thumb-piece, c, that is grasped firmly by the thumb and fingers of the operator in manipulating the machine. The key is carried by an arm or bar, C', which lies above the key-board, and is capable of horizontal movement transversely across the face of the board, and also vertically over the same, to adapt the pointed end of the key which it carries to enter any one of the numerous indentations or recesses in the key-board. The lower end of the arm or bar C', that carries the key, has lateral flanges c', which are bent at right angles at their free ends to provide the lugs c', that have transverse openings, which engage a guide and supporting rod or bar, F', on which the key-arm C' is free to turn or rotate as on a pivot in inserting or withdrawing the key into or away from the indentations of the key-board. This arm that carries the key can be moved very freely and easily over the rod F', longitudinally thereof, and the rod F' is carried or supported in a swinging frame, F, which

4C I will now proceed to describe.

The frame F comprises a rock-shaft, f, that is in rear of and partially concealed from view by the swinging key-board, and this shaft is journaled at or near its ends in suitable bearings, f', that are rigidly affixed to the base plate or piece A, the short arms or links f'', rigidly secured on and carried by the rock-shaft; the longer side arms, f'', which are pivotally connected with the free ends of the links 50 f'' by a rod or shaft, f', that passes through the contiguous ends of the said links and the arms, and the rod or guide F', hereinbefore described, secured in and carried by the outer free ends of the arms f'', which are each arranged to one side of and project beyond the swinging key-board for a very short distance to permit the rod or guide F' to move above and out of contact with the said board when the key C is moved or adjusted over the 55 board. To the rock-shaft f' is rigidly secured a key, F', which is in the form of a crank-arm and carries a finger-piece at its outer free end, so that it can be readily turned by the pressure thereon of the operator's hand, 60 the function of this key being to oscillate the rock-shaft and elevate the free ends of the links of the swinging frame to move the latter

and the key C vertically, for a purpose set forth hereinafter.

The type-cylinder D is arranged in an inclined position and substantially parallel with the swinging key-board and in rear of the latter, and this cylinder is carried by a longitudinally-movable and laterally-rotating support, D', that is fitted loosely on a shaft or rod, 75 d. This shaft d is affixed at its lower end to the swinging key-board in a very rigid and firm manner, so that the support and the type-cylinder are actuated simultaneously with the key-board, and the said shaft is arranged parallel with and extended beyond the upper edge of the key-board, so that the type-cylinder can have the required movement or play longitudinally to bring all of its longitudinally-arranged characters or letters to act upon the 80 paper in the paper-carriage. This type-cylinder is made of any desired material, and it is removably fitted on the support, so that when it is worn out through use, or any of the characters thereon have become broken or 85 otherwise so injured as to incapacitate the cylinder, it can be removed and another substituted. The characters and letters on the type-cylinder are arranged thereon so that when the key is inserted into one of the holes marked 90 with characters or letters on the key-board the corresponding letter or character on the type-cylinder will be brought into proper position to deliver its impression on the paper in the paper-carriage.

The following is the order of arrangement of the letters and characters on the type-cylinder when the arrangement of letters on the key-board above described is followed: The punctuation marks or characters, the dollar-mark, (\$,) and the cipher (0) are arranged in line around the periphery of the type-cylinder at the upper end thereof and occupy one row or series. Then follow the numerals or ordinals from one (1) to nine, (9,) inclusive, arranged in a second series or row around the periphery of the said type-cylinder. Then follow the small letters of the alphabet, which are arranged in three series or rows with nine in a series or row, and finally the capital or large letters arranged in like manner as the small letters—i. e., in three series or rows, with nine to a series. Of course the arrangement and disposition of the letters, ordinals, and characters are to be varied on the type-cylinder to 105 correspond with the arrangement of letters and characters on the key-board.

The carrier for the type cylinder is fitted loosely on the shaft d, so that it can rotate freely on the shaft, and also be capable of longitudinal sliding movement thereon, and the lower end of this carrier or support D' for the type-cylinder is provided with a band-pulley, G, around which pass and are secured the extremities of a band or cord, G', that is designed to communicate the motion of the key when it is moved across from side to side of the key-board to the type-cylinder to rotate the latter. The band or cord passes toward

1CC

105

110

115

120

125

130

the side edges of the swinging key-board and over small frictional rollers or pulleys *g*, which are journaled on suitable shafts or pins that are secured in the arms *f*³ of the swinging frame *F* 5 for the key, and said band also passes around the key-board to its upper face, and is connected with the key by means of a spring-clip, *G*², that is secured to and carried by the arm of the key, as shown. It will be seen 10 that when the key is moved in one direction across the key-board or from one side to the other the band will be drawn upon and slide freely over the guide-pulleys *g* and rotate the support or carrier for the type-cylinder to turn 15 or rotate the latter in one direction to bring one of the letters or characters thereon into position to deliver the impression onto the paper, and when the key is moved or drawn in the reverse or opposite direction the band 20 transmits the motion of said key to the carrier to turn or rotate the cylinder in the corresponding direction.

The rod or shaft *f*⁴ of the swinging frame *F*, that carries the single key, is provided with 25 two outwardly-extending arms, *h*, which are arranged at or near the middle of the shaft and on opposite sides of the support or carrier *D'* for the type-cylinder, and the outer free ends of the arms *h* are provided with lugs 30 or flanges *h*', which project inwardly toward each other and fit into a groove, *d*', formed in the lower free end of the support or carrier *D'*.

It will be seen that when the key-board is depressed or thrown forwardly by the action 35 of the key thereon the shaft *d*, the type cylinder, and the support or carrier for the said cylinder will be also depressed or lowered, so that the type-faces on the type-cylinder will be thrown into contact with the surface of the 40 paper in the carriage to deliver the inked impression onto the paper, and thus inscribe a letter or character thereon; and it will be further observed that when the key is moved up or down over the surface of the key-board the 45 shaft *F'*, the arms *f*², and the shaft *f*⁴ will be correspondingly moved with the key, so that the arms *h* of the shaft *f*⁴ will move or force the support or carrier *D'* and the type-cylinder up or down on the shaft *d*, this latter movement 50 being accomplished independently of any motion of the swinging key-board. The type-cylinder and the support therefor are thus capable of three independent motions, which are accomplished by separate and independent devices, which are as follows: first, a motion 55 imparted thereto by the swinging key-board to bring the type-surfaces of the said cylinder into contact with the paper in the carriage; second, an up-and-down movement on the shaft 60 *d*, which is imparted thereto by the swinging frame *F* when the key is moved up or down over the key-board, and, third, a lateral rotating movement on the shaft *d*, that is accomplished when the key is moved from one side 65 to the other or in a transverse line across the key-board, the band or cord moving freely

over the pulleys or guide-rollers *g* to actuate the support or carrier.

The links *f*², the rock-shaft, and the key *F*³, connected with the shaft, normally remain in 70 their position indicated in full lines in Fig. 2, so that the small letters of the type-cylinder are in position to act upon the paper; but when it is desired to print a capital letter on the paper the said key *F*³ is depressed to turn 75 the rock-shaft *f* and elevate the free ends of the links *f*², the arms *f*³, the shaft *f*⁴, and the arms *h* into a higher position to move the type-cylinder upwardly on the shaft *d* and bring 80 the capital letters on the lower portion of the cylinder into position for impressing the paper, as shown in Fig. 3, the key *C* being moved into either one of the lettered holes on the key-board. By this arrangement I am enabled 85 to dispense with a duplication of the alphabet on the key-board, and only inscribe thereon a single alphabet and a single set of lettered holes. The links *f*² normally occupy a horizontal position to permit the arms *f*³ to move on their pivots on the said links *f*², and 90 thereby enable the frame *F* to swing, when the key is adjusted or moved across the key-board, and in this position of the parts the small letters of the alphabet included in lines 3 to 5, inclusive, of the type-cylinder are adapted 95 to print on the paper when the swinging key-board is depressed, and in order to print capital letters the key *F*³ of the rock-shaft is depressed to elevate the type-cylinder and the swinging frame into a higher position to bring the capital letters of the alphabet included in lines 6 to 8, inclusive, of the cylinder into position to 100 deliver the impression of the proper letter on the paper of the carriage.

The type-faces on the type-cylinder extend 105 or project beyond the periphery of the said cylinder, and the said type-faces are inked by means of an inking-roller, *I*, that is normally in contact with the said type-faces, and is rotated by frictional contact therewith when 110 the type cylinder is rotated to keep all of the type constantly supplied with ink. The inking-roller is arranged parallel with and to one side of the type-cylinder, and the roller is loosely fitted on a shaft, *i*, that is arranged 115 parallel with the shaft *d*, and is secured on and carried by the swinging key-board. The inking-roller is thus depressed simultaneously with the key-board and the type-cylinder, and occupies the same relative position to the type-cylinder at all times, and the said roller is capable of longitudinal movement or play on its shaft simultaneously with the type-cylinder by means of annular flanges or rings on the ends of the type-cylinder which bear against 125 the ends of the inking-roller. The inking-roller is preferably of fabric of a suitable character which will absorb and retain the ink and supply the same freely to the type of the type-cylinder, and the inking-roller can be readily 130 renewed when worn or the ink therein has evaporated.

The paper-carriage E is arranged in rear of the type-cylinder and in an elevated position above the base plate or piece A. The carriage E comprises a flat piece of metal in the form of a bar or slide, which is provided at its ends with vertically-disposed flanges or lugs e, and the side edges of this slide are beveled or inclined, so that they will snugly fit within flanges e' of a way or track, E', that is rigidly affixed to a block, E'', which is secured on the base plate or piece A. The slide is free to move longitudinally in the track or way, as it is retained therein against lateral play to prevent the matter printed by the type-cylinder 15 from getting out of alignment. In the upper ends of the vertical lugs or flanges e of the slide is journaled a rock-shaft, j, which carries a swinging plate, J, that is normally arranged in a horizontal position and adapted 20 to be turned to an inclined or vertical position to move the carriage back and forth by the hand of the operator when desired. This swinging plate J extends beyond the edges of the carriage for a considerable distance, and 25 at its inner edge it has a depending rack-bar, j', with which engages the pawl k of the mechanism for feeding the carriage forward automatically when the machine is in operation, which mechanism I will describe hereinafter.

3c The said inner edge of the swinging plate J is further provided with vertically-disposed upward-extending bracket-lugs l, which are formed integral therewith and arranged at opposite sides of the said plate, and in these 35 bracket-lugs are journaled the shaft or trunions of a feed-roll, L. This feed-roll is made of rubber or other resilient material or substance to cushion the impact or blow of the type-cylinder when the latter is forced in contact 40 therewith to prevent injury to the type-faces, and the feed-roll is arranged in rear of the type-cylinder in such relative position thereto as to lie in the path of the type-cylinder to receive the impression from the inked faces of 45 the type thereon.

One end of the shaft, or one of the trunions of the feed-roll, is extended beyond one of the vertical bracket-lugs l and provided with a hand or finger piece, l', for the convenient rotation of the feed-roll by hand to turn the paper and bring another surface thereof into proper position to receive the impressions from the type-cylinder after one or the preceding lines have been printed.

55 The paper is held in proper position in the carriage and on the roller thereof by means of a clamp, M, which comprises the parallel arms or rods m, which are arranged on the upper and under surfaces of the feed-roll, the strips 60 m', rigidly affixed to and carried by the arms and inclined toward each other, and the yielding or spring arms m'', connecting the rods m, and serving to hold the strips m' in contact with the paper and to press the latter very 65 firmly against the periphery of the feed-roll. The lower arm or rod, m, is journaled at its extremities in openings or bearings in the

vertical bracket-lugs l of the swinging plate, and the spring or yielding arms m'' of the clamp M are arranged exteriorly to the said 70 lugs and the feed-roll, and the clamp can be turned or swung to bring the strips m' thereof away from the periphery of the feed-roll, so that the paper can be adjusted in, removed from, or fitted to the carriage, after which 75 the clamp is again adjusted to cause its strips m' to bear against and clamp the paper very firmly against the periphery of the feed-roll, so that it is held under tension and very firmly 80 in place, the paper being fed forward by the proper rotation of the feed-roll in the desired direction.

I will now proceed to describe the mechanism for feeding the carriage automatically with a step-by-step motion when the swinging key-board is depressed. The pawl k is provided with a bent lip at its outer free end, that is adapted to fit or take snugly in the teeth of the rack on the traveling carriage, and the opposite end of the pawl is pivoted 85 on and carried by a shaft, K, which is arranged in a horizontal position and at right angles to the carriage. The ends of this shaft K are provided with angular arms k', which are journaled in suitable bearings affixed to the base 90 A, so that the shaft can rock or oscillate back and forth to successively force the pawl into engagement with and withdraw it from the teeth of the rack to feed the carriage with a step-by-step motion, and the pawl is held or 95 supported in an elevated position by means of a spring, k'', that is coiled or wound around the rock-shaft and has a projecting lip to bear against the under surface of the pawl to raise the latter, for the purpose specified. One of 100 the right angled arms k' of the rock-shaft K has a bell-crank, n, connected therewith, and to the other end of this crank n is connected a vertically-disposed arm, n', the free end of 105 which is bent and secured to the rear concealed surface of the swinging key-board, a spring, N, being connected with the bell-crank n to elevate the arm n' and the key-board after each depression of the key-board. When 110 the key-board is depressed, the arm n' is likewise operated against the tension of the spring N to move the crank n and force the rock-shaft K in one direction, and thus withdraw the pawl from engagement with the teeth on the rack of the carriage, and when the pressure of the key on the key-board is released or 115 withdrawn the spring N again elevates the arm n' to return the key-board to its normal position for instant operation again, and also throws the rock-shaft K in the opposite direction to move the pawl k and feed the carriage 120 one step forward, the free end of the pawl k being forced or elevated into the proper tooth on the rack of the carriage by the spring k''.

O designates the space-key for moving the 125 carriage with a step-by-step motion independently of the mechanism for automatically feeding the carriage. The space-key is for the purpose of properly spacing the words apart,

and is to be actuated one or more times after each word has been written or printed. The key O is arranged in rear of the swinging key-board and projects at its free end beyond the 5 side edge of the said key-board, where it is provided with a finger-piece for its convenient manipulation, and the opposite end of the key is provided with a right-angled arm, o, which is journaled in a suitable bearing that is affixed 10 to the base A of the machine. The arm o carries a vertically-disposed arm or rod, o', which in turn carries a swinging or rock shaft, O', and on this shaft O' is pivotally supported one end of a pawl, P, which has its free end projected or extended toward the pawl k and provided with a nib or shoulder, p, which is normally depressed below the plane of the free end of the pawl k and out of the line of movement of the rack on the carriage by means of 15 a spring, p', which encircles the shaft O' and bears at one end against the said pawl, as clearly shown. To operate the space-key to separate two contiguous words on the paper of the carriage E, the free end of the key is depressed by bearing or pressing downwardly thereon to draw the shaft O' and the arm o' to one side and in the direction which the said carriage moves, and by this means the pawl P is withdrawn from beneath the pawl k, and is 20 elevated so that its tooth or shoulder takes into one of the teeth of the rack on the carriage to feed the latter forward one step, and thus effect the proper spacing of the words, and when the pressure of the operator's fingers 25 30 35 40 45 50 55 draw the rack thereof from engagement with the pawl *k*, so that the carriage can be returned to the right to begin a new line, the feeding of the paper and return movement of the carriage being effected simultaneously by the operator grasping the finger-piece of the feed-roll.

My improved machine is compact and simple in construction and arrangement, very durable and reliable in operation, and can be easily and readily transported from one place to another, which is very desirable. With a little practice the machine can be operated very rapidly and ready access to the parts can be had to clean and repair the machine.

I do not intend to confine myself to the exact construction herein shown and described as an embodiment of my invention, as I am aware that numerous changes therein can be made without departing from the spirit of my invention.

Having thus fully described my invention, what I claim as new, and desire to secure by Letters Patent of the United States, is—

1. In a type-writing machine, the combination of a swinging key-board, a type-cylinder carried by the key-board, a swinging frame capable of rocking motion and connected with the type-cylinder to move the latter obliquely, a key carried by the swinging frame and connected with the type-cylinder to rotate the latter when the key is moved across the key-board, and a traveling carriage having a step-by-step motion and arranged to receive the impressions from the type-cylinder, substantially as described, for the purpose set forth.

2. In a type-writing machine, the combination of a swinging key-board, an oblique rod secured to said key-board, a type-cylinder carried by said rod and capable of longitudinal movement and lateral rotation thereon, a single key connected with and controlling the position of said type-cylinder, a traveling carriage to receive the impressions from the type-cylinder, and mechanism, substantially as described, intermediate of the key-board and carriage for feeding the latter with a step-by-step motion upon the return of the key-board to its normal position, as set forth.

3. In a type-writing machine, the combination of a swinging key-board, an oblique rod secured thereto, a type-cylinder carried by the said rod and capable of longitudinal movement and lateral rotation thereon, a single key connected to and controlling the position of said type-cylinder, a traveling carriage arranged to receive the impressions from the type-cylinder, said carriage being provided with a rack, and a rock-shaft carrying a pawl which engages said rack, said rock-shaft being secured upon the base of the machine and connected to the key-board, so as to feed the carriage with a step-by-step motion.

4. In a type-writer, the combination of a swinging key-board, a type-cylinder carried by said key-board and arranged below the same and capable of longitudinal movement and

lateral rotation, an inking roller carried by the key-board and arranged parallel to and in contact with the type-faces of the type-cylinder and movable therewith, a single key connected to the type-cylinder to control the position of the same, and a traveling carriage arranged in the path of the type-cylinder, substantially as described.

5. In a type-writer, the combination of a swinging key-board, a type-cylinder carried by said key-board having annular flanges at its opposite ends and being capable of longitudinal movement and lateral rotation, an inking-roller, also carried by the key-board, arranged in contact with the type-cylinder, and having its opposite ends acted upon by the annular flanges on the type-cylinder, a single key connected with the type-cylinder and controlling its movements, and a traveling carriage arranged in the path of the type-cylinder, substantially as specified.

6. In a type-writing machine, the combination of a swinging key-board, a rock-shaft, *f*, carrying a key and the arms *f*², normally arranged in a horizontal position, a swing-frame carried by the arms and adapted to be elevated when the rock-shaft is turned by depressing the key, a type-cylinder supported on the key-board and connected with the swinging frame to be moved longitudinally thereby, a single key, *C*, fitted on the swinging frame and connected with the type-cylinder to rotate it, and a traveling carriage, substantially as described, for the purpose set forth.

7. In a type-writing machine, the combination of a swinging key-board, a type-cylinder carried thereby, a key or pointer connected with the type-cylinder, a swinging frame carrying the key, and also connected to the type-cylinder, a traveling carriage, mechanism, substantially as described, actuated by the swinging key-board for automatically feeding the carriage with a step-by-step motion, and a space-key for feeding the carriage with a step-by-step motion independently of the swinging key-board, substantially as described.

8. In a type-writing machine, the combination of a swinging key-board, a pivoted frame having the bar *F*' and the arms *h*, a key carried by an arm that is free to slide longitudinally on the bar, the guide-rollers carried by the frame, a type-cylinder carrier or support having the pulley secured to the key-board, the type-cylinder fitted on said carrier, the band connected with the key and the pulley of the carrier and passing over the guide-rollers, and the traveling carriage arranged in the path of the type-cylinder, substantially as described.

9. The combination of a swinging key-board, the pivoted frame, a key or pointer supported on the frame, the parallel shafts *d* *i*, secured on the key-board, a type-cylinder fitted on the shaft *d* and connected with the key, an inking-roller journaled on the shaft *i* and hav-

ing its periphery in contact with the type-cylinder, and a traveling carriage, substantially as described.

10. In a type-writing machine, the combination of a swinging key-board, a type-cylinder carried by the said key-board and having a series of radial pins arranged in line with each other around the periphery thereof, the inclined guide-plate having a series of apertures or recesses into which the pins are adapted to fit when the type-cylinder is depressed, a key connected with the type-cylinder, a swinging frame for moving the type-cylinder longitudinally and carrying the key, and a traveling carriage, substantially as described.

11. The combination of a track or way, a slide fitted and movable longitudinally therein, a swinging plate journaled in bearings on the slide and carrying a rack, a feed-roller 20 journaled on the plate, a rock-shaft carrying a pawl to mesh with the rack in the swinging plate, and mechanism, substantially as described, for oscillating the rock-shaft, substantially as described.

In testimony that I claim the foregoing as my own I have hereto affixed my signature in presence of two witnesses.

JAMES W. CHRYSSTY.
